BELL HOIST

Application filed January 26, 1928. Serial No. 249,607.

This invention relates to bell hoisting mechanism for use in connection with blast furnaces.

It is necessary in the operation of blast furnaces to provide furnace charging mechanism to introduce certain mixtures of ore, coke or coal, and lime into the furnace. It is also necessary when placing the mixture or charge within the furnace to keep the furnace air-tight. It is possible to place the charge within the furnace and at the same time keep the furnace air-tight by providing a receiving compartment upon the top of the furnace. The upper portion of the compartment is provided with an opening for receiving the charge and the lower portion of the compartment is provided with a larger opening leading to the furnace through which the charge may pass. The upper opening is normally closed by a small charging bell and the lower opening is normally closed by a large charging bell. A hopper leading to the small bell is usually placed upon the compartment. When it is desired to charge the furnace, portions of ore, coke or coal, and lime are successively carried to the hopper by means of a skip or hoist and admitted to the compartment through the upper opening by moving the small bell to its open position, the small bell being closed after each portion has been dumped into the compartment; the large bell is closed during the charging of the compartment. When the proper mixture has been formed within the compartment the large bell is moved to its open position, thereby allowing the entire mixture to be dumped into the furnace, the small bell remaining closed during this operation.

It is desirable that a machine be employed for operating the bells that will permit any desired cycle of operation, since it is often necessary to vary the number of times the small bell is operated for one operation of the large bell. It is further desirable that the bells be gradually and rapidly moved to and from their seats.

One feature of the invention is the provision of hoisting mechanism employing a

single operating motor for operating both the large bell and the small bell.

A second feature of the invention is the provision of a rotary operating member for each bell, the operating member of a bell upon being rotated from a neutral position causing its bell to open and upon being returned to the neutral position allowing its bell to close.

A third feature of the invention is the provision of a rotary driving member, operated by the motor, for causing the operating members to rotate, the driving member by rotation in one direction causing one of the operating members to open its bell, and by rotation in the other direction causing the other of the operating members to open its bell.

A fourth feature of the invention is the provision of hoisting mechanism wherein gradual acceleration of the load is secured by means of crank action and wherein thereafter a substantially constant speed of the load is secured by means of drum action.

A fifth feature of the invention is the provision of bell hoisting mechanism wherein each bell is gradually accelerated from its closed position by means of crank action and thereafter rapidly moved to its open position by means of a drum action, and wherein each bell is rapidly moved toward its closed position by means of a drum action and thereafter retarded in its final closing movement by means of a crank action.

A sixth feature of the invention is the provision of a bell hoisting mechanism in which the hoisting machine and motor are of a minimum size for a given installation.

A seventh feature of the invention is the provision of a bell hoisting mechanism in which the bells are positively moved to their open position.

Other features and advantages will become apparent from the following description and appended claims.

In the drawings:—

Figure 1 is a schematic representation of the upper portion of a blast furnace illustrating the adaptation of the bell hoisting mechanism to the charging mechanism and showing

ing the small bell in its open position and the large bell in its closed position;

Figure 2 is a plan of the bell hoisting machine with portions broken away to illustrate certain structural details;

Figure 3 is an elevation of the bell hoisting machine with a portion shown in section, taken along the line 3—3 of Figure 2, and with portions broken away to illustrate certain structural details;

Figure 4 is a view in section taken along the line 4—4 of Figure 3 showing the positions of the operating lugs and drum abutments when the parts are in their neutral position; and

Figure 5 is a view in section taken along the line 5—5 of Figure 4.

Referring to Figure 1, a blast furnace 11 is provided with a compartment 12 at its upper end for receiving a charge of ore, coke or coal, and lime, or other material. Mounted upon the upper portion of compartment 12 is a hopper 13 extending into the compartment. The lower end of compartment 12 is normally closed by a large bell 15 and the upper end of compartment 12, leading into hopper 13, is normally closed by a small bell 14. Small bell 14 is connected by means of a hollow rod 16 to one end of a lever or walking beam 17, the lever 17 being pivotally supported by a fulcrum 18. Lever 17 carries at its opposite end a counterweight 21 of sufficient mass to counterbalance the weight of bell 14 and rod 16 plus the weight of the load of material (not shown) resting thereon, and to provide in addition a sufficient force to maintain a heavy sealing pressure between bell 14 and its seat. Large bell 15 is connected by means of a rod 22 to a lever 23, the lever 23 being pivotally supported by a fulcrum 19. Rod 22 extends up through hollow rod 16. Lever 23 is likewise provided with a counterweight, designated by the numeral 24, counterweight 24 counterbalancing the weight of bell 15 and rod 22 as well as the charge and providing sufficient sealing pressure between bell 15 and its seat.

A hoisting machine 25 is provided for operating small bell 14 and large bell 15. Drums 26 and 27 are loosely mounted upon a shaft 28, bearings 31 being provided for shaft 28. Bearings 31 are supported by a machine base 32. A hoisting cable 39 for small bell 14 has a section of chain 33 at its lower end secured to drum 26 by means of a pin 34, cable 39 passing over stationary pulleys 35 and 36 and being connected to lever 17 at its weighted end. A hoisting cable 40 for large bell 15 has a section of chain 37 at its lower end secured to drum 27 by means of a pin 38, cable 40 passing over stationary pulleys 41 and 42 and being connected to lever 23 at its weighted end. Thus, rotation of drum 26 from its neutral position, shown in Figures 2 and 3, causes cable 39 to move the weighted end of lever

17 upwardly thereby opening small bell 14, and rotation of drum 27 from its neutral position, shown in Figures 2 and 3, causes cable 40 to move the weighted end of lever 23 upwardly thereby opening large bell 15. A driving gear 43 is keyed to shaft 28.

Referring to Figures 2 to 5 inclusive, drums 26 and 27 and driving gear 43 are shown in their neutral position. Bolted to the side of the center of driving gear 43 adjacent drum 75 26 is a lug 44 and bolted to the side of the center of driving gear 43 adjacent drum 27 is a lug 45. An abutment 46 is mounted upon drum 26 in the path of movement of lug 44 and an abutment 47 is mounted upon drum 27 80 in the path of movement of lug 45. When driving gear 43 is rotated from its neutral position in a counter-clockwise direction, as viewed in Figures 1 and 3, its lug 44 moves to the left, as viewed in Figures 2 and 4, and 85 engages abutment 46 of drum 26, causing the drum to rotate with the gear thereby opening small bell 14; as driving gear 43 so moves, its lug 45 moves away from abutment 47 of drum 27, drum 27 remaining in its neutral 90 position. When driving gear 43 is rotated from its neutral position in a clockwise direction, as viewed in Figures 1 and 3, its lug 45 moves to the right, as viewed in Figures 2 and 4, and engages abutment 47 of drum 27, 95 causing the drum to rotate with the gear thereby opening large bell 15; as driving gear 43 so moves, its lug 44 moves away from abutment 46 of drum 26, drum 26 remaining in its neutral position.

A motor 48 mounted upon base 32 is provided for causing driving gear 43 to rotate in one direction or the other. A reversing switch 4 is indicated for energizing the armature of the motor to cause it to rotate in the desired direction. A gear train 51 employed to transmit motion from motor 48 to driving gear 43. Connected to motor shaft 52 is a worm gear 53, worm gear 53 meshing with an external gear 54 keyed to a shaft 55. 100 Bearings 56, supported by base 32, are provided for shaft 55 and bearings 57 are provided for worm gear 53. A pinion 58 keyed to shaft 55 is in mesh with driving gear 43 for causing gear 43 to rotate upon rotation of shaft 55. A guard 59 is provided for covering driving gear 43 and pinion 58, a casting 61 being provided for external gear 54.

A brake 60 is provided for bringing the rotating members rapidly to rest when the motor is deenergized. The brake is shown as spring applied and electrically released.

In operation, when a load of coke, or ore, or other material, has been dumped into hopper 13 and it is desired to dump the load into compartment 12, motor 48 is energized to cause driving gear 43 to rotate from its neutral position in a counter-clockwise direction, as viewed in Figures 1 and 3, whereby lug 44 engages abutment 46 on drum 26 caus-

ing the drum to rotate from its neutral position. Chain 33, in the neutral position of drum 26, extends in a direction radial to the axis of the drum. As drum 26 rotates, 5 pin 34 to which chain 33 is attached moves in a circular arc to gradually open small bell 14, and when drum 26 is rotated approximately 90 degrees, chain 33 becomes tangential to the surface of the drum and thereafter chain 33 is wound upon the drum to rapidly move bell 14 to its full open position, bell 14 being fully open when drum 26 has rotated approximately three-quarters of a revolution. The material is then dumped 10 into compartment 12. The small bell is then in the position shown in Figure 1. Motor 48 is then deenergized, and brake 60 is applied to bring the moving parts to rest.

In closing bell 14, the reverse operation 20 takes place, motor 48 being reversed to allow drum 26 to rotate in the opposite direction under the influence of weight 21. When small bell 14 is closed, motor 48 is deenergized and brake 60 is applied to bring the moving parts to rest. The above operation 25 may be repeated as often as desired until the proper quantity of material has been dumped into compartment 12. When it is desired to dump the mixture into furnace 11, motor 30 48 is energized to cause driving gear 43 to rotate from its neutral position in a clockwise direction, as viewed in Figures 1 and 3, whereby lug 45 engages abutment 47 on drum 27 causing the drum to rotate from its 35 neutral position. Chain 37 in the neutral position of drum 27 extends in a direction radial to the axis of the drum. As drum 27 rotates, pin 38 to which chain 37 is attached moves in a circular arc to gradually open large bell 15, and when drum 27 is rotated 40 approximately 90 degrees, chain 37 becomes tangential to the surface of the drum and thereafter chain 37 is wound upon the drum to rapidly move bell 15 to its full open position, 45 bell 15 being fully open when drum 27 has rotated approximately three-quarters of a revolution. The material is then dumped into furnace 11. When bell 15 is fully opened, motor 48 is deenergized and brake 60 is applied to bring the moving parts to rest. Motor 48 is then reversed allowing large 50 bell 15 to close under the influence of weight 24, chain 37 first unwinding and then gradually assuming a radial direction.

55 It is occasionally necessary to open both bells to allow the furnace to breathe. This may be accomplished as follows: Driving gear 43 is rotated until the small bell is opened. Hoisting cable 33 of small bell 14 is then anchored to a fixed support, as for example, by a hook 29. Driving gear 43 is then reversed until large bell 15 is opened.

60 It is to be noted that for the first quarter of a revolution of either drum from its neutral position, the machine operates with a

crank action, thus providing gradual acceleration and reducing shock at starting. For the remainder of the travel, the machine operates with a drum action and the hoisting cable travels at the same speed as the surface of the drum. In closing movement the 70 operation is reversed, that is, the cable travels at full speed until the drum is within one-quarter of a revolution from the neutral position. At this point, the drum action ceases 75 and the crank action comes into effect, thereby slowing down the speed of the bell to the closing and sealing point. This arrangement permits the use of a motor of minimum horse power and a machine of minimum proportions. 80

It is pointed out that it is impossible to open both of the bells at the same time. Rotation of the driving gear in one direction from neutral position can only operate a single bell, the other bell being held tightly against its seat by its counterweight. Rotation of the driving gear in the other direction from its neutral position can only operate the other bell. It is impossible therefore for 90 furnace leakage to occur.

It is also pointed out that the bell hoisting machine is extremely flexible in operation. Any cycle of operation may be had, 95 since the small bell may be repeatedly operated without the large bell being moved from its closed position, or the large bell may be repeatedly operated, if desired, without the small bell being moved from its closed position.

100 It is further pointed out that no damage can occur to the operating parts by reason of failure to stop the motor when either of the bells has been moved to its closed position because the gear disengages the drum, being moved to close a bell, upon the drum reaching neutral position.

105 As many changes could be made in the above construction and many apparently widely different embodiments of this invention could be made without departing from the scope thereof, it is intended that all matter contained in the above description or shown in the accompanying drawings shall be interpreted as illustrative and not in a 110 limiting sense.

115 What is claimed is:

1. In a furnace charging mechanism having a small bell and a large bell, actuating mechanism for the bells, said actuating mechanism comprising; a rotary member operably connected to the small bell, said rotary member upon rotating from a neutral position causing the small bell to open; a second rotary member, the axis of said second rotary member being coincident with the axis of said first rotary member, operably connected to the large bell, said second rotary member upon rotating from a neutral position causing the large bell to open; a motor; means for causing 120
- 125
- 130

connection between said motor and said rotary members to be effected only with respect to said first mentioned rotary member upon operation of said motor in one direction for causing only that member to rotate from its neutral position by said operation of said motor in one direction; and means for causing connection between said motor and said rotary members to be effected only with respect to said second mentioned rotary member upon operation of said motor in the other direction for causing only that member to rotate from its neutral position by said operation of said motor in the other direction.

2. In a furnace charging mechanism having a small bell and a large bell, actuating mechanism for the bells, said actuating mechanism comprising; a rotary member operably connected to the small bell, said rotary member upon rotating from a neutral position in one direction causing the small bell to open; a second rotary member, the axis of said second rotary member being coincident with the axis of said first rotary member, operably connected to the large bell, said second rotary member upon rotating in the opposite direction from a neutral position causing the large bell to open; a motor; means for causing connection between said motor and said rotary members to be effected only with respect to said first rotary member for causing said member to rotate in said one direction from its neutral position without causing rotation of said second rotary member; and means for causing connection between said motor and said rotary members to be effected only with respect to said second rotary member for causing said member to rotate in said opposite direction from its neutral position without causing rotation of said first rotary member.

3. In a furnace charging mechanism having a small bell and a large bell, actuating mechanism for said bells, said actuating mechanism comprising; a rotary member operably connected to the small bell, said rotary member being in a neutral position when the small bell is closed; a second rotary member operably connected to the large bell, said second rotary member being in a neutral position when the large bell is closed; a motor; clutch members interposed between said motor and said first rotary member and engaging, upon operation of said motor in one direction, to connect that member to said motor to be rotated thereby from its neutral position to open the small bell; and additional clutch members interposed between said motor and said second rotary member and engaging, upon operation of said motor in the opposite direction, to connect that member to said motor to be rotated thereby from its neutral position to open the large bell.

4. In a furnace charging mechanism having a bell, actuating mechanism for the bell,

said actuating mechanism comprising; a rotary member for effecting operation of the bell, said rotary member being in a neutral position when the bell is closed; flexible transmission means operably connecting said rotary member and the bell, said flexible transmission means being secured to said rotary member and extending radially therefrom when said rotary member is in neutral position; and means for rotating said rotary member from its neutral position to effect the opening of the bell, said flexible transmission means being shifted from its radial position upon such rotation of said rotary member, and assuming a tangential position with respect to said rotary member when said member has rotated approximately 90 degrees and thereafter being wound upon said rotary member.

5. In a furnace charging mechanism having a small bell and a large bell, actuating mechanism for the bells, said actuating mechanism comprising; a lever supporting the small bell; a weight acting upon the lever for biasing the small bell to closed position; a lever supporting the large bell; a weight acting upon the lever for biasing the large bell to closed position; a motor; means for operably connecting the motor to the first mentioned lever for causing the lever to move the small bell to open position against the force of the small bell weight by operation of said motor in one direction; and means for operably connecting the motor to the second mentioned lever for causing the lever to move the large bell to open position against the force of the large bell weight by operation of said motor in the opposite direction.

6. A furnace charging mechanism having a small bell and a large bell, actuating mechanism for the bells, said actuating mechanism comprising; a lever supporting the small bell; a weight acting upon the lever for biasing the small bell to closed position; a second lever supporting the large bell; a weight acting upon the lever for biasing the large bell to closed position; a motor; means for operably connecting the motor to the first mentioned lever, when the motor operates in one direction from a given position, for causing the lever to move the small bell to open position against the force of the small bell weight, and for thereafter allowing the small bell to close under the influence of said weight when the motor is reversed; and means for operably connecting the motor to the second lever, when the motor operates in the other direction from said given position, for causing the second lever to move the large bell to open position against the force of the large bell weight, and for thereafter allowing the large bell to close under the influence of said weight when the motor is reversed.

7. A furnace charging mechanism having a small bell and a large bell, actuating mech-

anism for the bells, said actuating mechanism comprising; means biasing the small bell to its closed position; means biasing the large bell to its closed position; a rotary member 5 loosely mounted upon the shaft and operably connected to the small bell, the rotary member upon being rotated from a neutral position causing the small bell to open; a rotary member loosely mounted upon the shaft and operably connected to the large bell, the rotary member upon being rotated from a neutral position causing the large bell to open; a motor; means for operably connecting the motor to the first mentioned rotary member 10 for causing said member to rotate to open the small bell against the force of its biasing means, when the motor is energized to rotate in one direction, the motor being deenergized when the bell is fully opened; means 15 for operably connecting the motor to the second mentioned rotary member for causing said member to rotate to open the large bell against the force of its biasing means, when the motor is energized to rotate in the other direction, the motor being deenergized when 20 the bell is fully opened; and means cooperating with either rotary member for causing that member to hold its bell in open position against the closing biasing means, when that member has moved its bell to open position 25 and the motor has been deenergized. 30

8. In a furnace charging mechanism having a small bell and a large bell, actuating mechanism for the bells, said actuating mechanism comprising; means biasing the small bell to its closed position; means biasing the large bell to its closed position; a shaft; a rotary member loosely mounted upon the shaft and operably connected to the 35 small bell, the rotary member upon rotating from its neutral position causing the bell to open against the force of the biasing means; a second rotary member loosely mounted upon the shaft and operably connected to the 40 large bell, said second rotary member upon rotating from its neutral position causing the large bell to open against the force of the biasing means; a rotary driving member keyed to the shaft; means for connecting the 45 driving member to the first mentioned rotary member as the driving member is rotated in one direction for causing the first mentioned rotary member to rotate from its neutral position; means for connecting the driving 50 member to the second mentioned rotary member as the driving member is rotated in the other direction for causing the second mentioned member to rotate from its neutral position; and means for causing the rotary driving member to rotate in one direction or the other as desired. 55

9. In a furnace charging mechanism having a small bell and a large bell, actuating mechanism for the bells, said actuating mechanism comprising; a lever supporting 60

the small bell; a weight acting upon the lever for biasing the small bell to closed position; a lever supporting the large bell; a weight acting upon the lever for biasing the large bell to closed position; a shaft; a rotary member 65 loosely mounted upon the shaft; flexible means operably connecting said rotary member and the small bell lever, said rotary member upon rotating from its neutral position causing the small bell to open against the force of its biasing weight; a second rotary member 70 loosely mounted upon the shaft; flexible means operably connecting the second mentioned rotary member to the large bell lever, said second rotary member upon rotating from its neutral position causing the large bell to open against the force of its biasing weight; a rotary driving member keyed to the shaft; means for connecting the driving member to the first mentioned rotary member, when the driving member is rotated in one direction, for causing the first mentioned rotary member to rotate from its neutral position; means for connecting said driving member to said second rotary member, when 75 said driving member is rotated in the other direction, for causing said second rotary member to rotate from its neutral position; and a motor for rotating said driving member in one direction or the other as desired. 80

10. In a furnace charging mechanism having a small bell and a large bell, actuating mechanism for the bells, said actuating mechanism comprising; means for biasing the small bell to its closed position; means for biasing the large bell to its closed position; a shaft; a pair of drums loosely mounted upon the shaft, one drum for each bell; an abutment mounted upon each drum; a flexible transmission means for the small bell, one end of the flexible transmission means being connected to the small bell, the other end of the flexible transmission means being connected to the small bell drum; a second flexible transmission means for the large bell, one end of the transmission means being connected to the large bell, the other end of the transmission means being connected to the large bell drum; a rotary driving member keyed to the shaft; a lug mounted upon the driving member for engaging the abutment upon the small bell drum when the driving member is rotated in one direction from a neutral position, thereby causing the drum to rotate for drawing the connected flexible transmission means to open the small bell; a lug mounted upon the driving member for engaging the abutment upon the large bell drum when the driving member is rotated in the other direction from a neutral position, thereby causing the drum to rotate for drawing the connected transmission means to open the large bell; and an electric motor for rotating the driving member in one direction or the other as desired. 115

11. In a furnace charging mechanism having a small bell and a large bell, actuating mechanism for the bells, said actuating mechanism comprising; means for biasing the small bell when loaded to closing position; means for biasing the large bell when loaded to fully closed position; a shaft; a pair of drums loosely mounted upon the shaft, one drum for each bell, each of the drums being provided with an abutment, the abutments being located at equal radial distances from the shaft axis; a hoisting cable for the small bell, one end of the small bell cable being connected to the 15 small bell, the other end of the small bell cable being connected to the periphery of the small bell drum; a hoisting cable for the large bell, one end of the large bell cable being connected to to 20 the large bell, the other end of the large bell cable being connected to the periphery of the large bell drum; a driving gear keyed to the shaft; a lug mounted upon one side of the driving gear, adjacent the small bell 25 drum; said lug engaging said small bell drum abutment for rotating said small bell drum when the driving gear is rotated in one direction, thereby drawing the small bell cable to open the small bell; a second lug mounted upon the other side of the driving gear adjacent the large bell drum; said second lug engaging said large bell drum abutment for 30 rotating said large bell drum when the driving gear is rotated in the opposite direction, thereby drawing the large bell cable to open the large bell; and an electric motor geared to the driving gear for rotating the driving gear in one direction or the other as desired.

In testimony whereof, I have signed my
40 name to this specification.

ARTHUR E. HANDY.
